UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

ROUTING MACHINE.

Application filed May 15, 1925. Serial No. 30,515.

My invention relates to routing machines for lasts.

It is the object of my invention to provide a routing machine for forming the grooves in the heel and toe parts of the lasts in such a way that both the toe and heel part of the lasts may be routed successively in the same machine and so that a plurality of heel and toe parts may be routed in the same way to give uniform production.

It is my object to eliminate variations in production and to facilitate production by providing a machine which when once set will rout the parts of the lasts uniformly and rapidly.

It is a further object to provide a routing machine in which the routing can be done with the least opportunity for injury to the operator.

It is a further object to provide means of holding the last parts in predetermined fixed positions, utilizing the established holes in the last parts through which the anchor pins are afterwards inserted.

It is a further object to provide a machine which is adjustable quickly and positively to varying sizes of lasts so that one machine may be adaptable to any type or form of last.

Referring to the drawings:—

Figure 1 is a front elevation of the complete machine;

Figure 2 is a side elevation of the complete machine;

Figure 3 is an elevation of the last holding mechanism;

Figure 4 is a plan view thereof;

Figure 5 is a view taken on the line 5—5 of Figure 3 looking in the direction of the arrows;

Figure 6 is a plan view of the table with the holding frame in section showing the mechanism for shifting the table and holding frame; and

Figure 7 is an enlarged detail and side elevation of the last supporting mechanism.

Referring to the drawings, 1 is a supporting base which has an overhanging arm 2 from which depends a supporting arm 3 in which is journalled a shaft 4 operated by a hand wheel 5. A table slide 6 is provided which can be moved to and from the operator. On this table slide mounted in a dove

tail is the table 7. Mounted on the table slide is a pin 8 upon which is pivoted the lever 9 for shifting the table 7 laterally in the table slide 6. The support 1 carries a housing 10 at the rear of the machine in which is journalled the routing tool shaft 11. On one end of this shaft is carried a pulley 12 operated by a belt 13 from a suitable source of power. On the other end of the shaft held in the chuck 14 is the routing tool 15. A suitable pipe connected to a blower for carrying away the dust is located at 16.

Turning to the table 7, at one end a link 17 is pivoted thereto at 18. The other end of the link is pivoted to the lever 9 at 19 so that by a transverse movement of the lever the table 7 may be moved laterally. Mounted upon this table is a rectangular holding frame consisting of a base member 20, side members 21 and a cap member 22. In this cap member there are journalled two screws 23 operated by handles 24 and having on the lower ends of such screws the positioning or holding pins 25 which are adapted to be inserted in one end of the hole in a last part in which the anchor pin is normally located. Corresponding pins 26 directly beneath the pins 25 are located on the base member 20.

The holding frame is arranged to be moved forwardly or rearwardly on the table 7 through slots 27 in which are located positioning bolts 28.

On the side away from the operator mounted upon the table 7 are a pair of spaced rectangular plates 29 having a pair of slots 30 and 31 in which are located positioning bolts 32. These slide plates 29 carry a positioning screw 33 having a broad flat head 34 upon which a part of the last rests.

Thus the last half can be mounted with its hinge side towards the routing tool 15 which is to form a mortise in it by mounting the last with the pin 26 in the under side of the anchor pin hole and the pin 25 to the upper side of the anchor pin hole.

For instance, 35 designates the last and 36 the mortise which results from the routing to form a mortise for the hinge springs and links.

The last can be swung upon the pins 25 and 26 so that the routing tool may form 108 the mortise desired. The plate 34 forms a

broad bearing for the last part directly beneath the portion being routed.

The shaft 4 carries on its inner end a bevelled gear 37 meshing with a similar bevelled gear 5 at right angles thereto 38 carried on the upper end of a worm shaft 39 which turns in a bracket 40. Thus it is possible to elevate the entire platform upon which the apparatus rests through the slide members 10 44 working on the guide 42 of the support 1.

Mode of operation.

The last parts 35 are each placed on the broad flat head 34 and the pins 26 project into the usual perforations in the last parts. 15 The upper pair of holding pins 25 are then lowered by means of operating handles 24 and thereby causing said pins 25 to project into the last parts.

20 When it is desired to bring the routing tool 15 in contact with one of the last halves, the operator grasps the lever 9 and moves it to the right, thereby causing the plate 7 to also move in the same direction along the slide 6. The last parts are elevated or lowered relative to the position of the tool 15 for cutting purposes by rotating the hand wheel 5, thereby transmitting motion through the bevelled gear 37 and 38 respectively, and since 25 worm 39 is threaded in fixed bracket 40, the rotary motion will cause the entire platform to move in a vertical direction in the slide 42. It is also to be noted that the holding frame 21 may be moved forwardly or rearwardly 30 on the table 7 through slots 27 in which are located positioning bolts 28.

The flat heads 34 which support a part of 40 the last halves are also adjustable vertically and laterally with respect to the tool 15, by means of the pair of plates 29 mounted on the tables 7 through the pair of slots 30 and 31 in which are positioning bolts 32.

45 It will be seen from the preceding description that the members 34 may be adjusted vertically by two separate means.

50 Thus it will be apparent that the holding device is adapted for vertical, lateral, forward and rearward movement with respect to the position of the routing tool 15, so that last halves held by the device may be suitably mortised.

55 It will be understood that I desire to comprehend within my invention such modifications as may be necessary to adapt it to varying conditions and uses.

Having thus fully described my invention, what I claim as new and desire to secure by Letters Patent, is:—

60 1. In a routing machine, a work holder comprising a supporting plate, a frame, a positioning pin mounted on the bottom of said frame, an adjustable positioning pin mounted on the top of said frame carried by said plate and adapted to be lowered into engagement with a hole in a last half, said

lower pin also adapted to project into the hole from the opposite side of said last half, thereby permitting pivotal movement of the last half in order to permit interior enlargement of the mortise by a routing tool, said work holder so mounted that it may be moved axially toward and transversely of said tool and a routing tool. 70

2. In a routing machine, a work holder comprising a supporting plate, a frame, a 75 positioning pin mounted on the bottom of said frame, an adjustable positioning pin mounted on the top of said frame carried by said plate and adapted to be lowered into engagement with a hole in a last half, said lower pin also adapted to project into the hole from the opposite side of said last half, thereby permitting pivotal movement of the last half in order to permit interior enlargement of the mortise by a routing tool, said work holder so mounted that it may be moved axially toward and transversely of 80 said tool and a routing tool, and means to support the under portion of the last half adjacent the routing tool. 85

3. In a routing machine, a work holder comprising a supporting plate, a frame, a positioning pin mounted on the bottom of said frame, an adjustable positioning pin mounted on the top of said frame carried by 90 said plate and adapted to be lowered into engagement with a hole in a last half, said lower pin also adapted to project into the hole from the opposite side of said last half, thereby permitting pivotal movement of the last half in order to permit interior enlargement of the mortise by a routing tool, said work holder so mounted that it may be moved axially toward and transversely of 95 said tool and a routing tool, and means to support the under portion of the last half adjacent the routing tool, said support having a broad bearing surface. 100

4. In a routing machine, a work holder comprising a supporting plate, a frame, a 110 positioning pin mounted on the bottom of said frame, an adjustable positioning pin mounted on the top of said frame carried by said plate and adapted to be lowered into engagement with a hole in a last half, said lower pin also adapted to project into the hole from the opposite side of said last half, thereby permitting pivotal movement of the last half in order to permit interior enlargement of the mortise by a routing tool, said work holder so mounted that it may be moved axially toward and transversely of 115 said tool and a routing tool, and means to support the under portion of the last half adjacent the routing tool, said support having a broad bearing surface and means to adjust the position of said frame on said plate. 120

5. In a routing machine, a work holder comprising a supporting plate, a frame, a 125

- positioning pin mounted on the bottom of said frame, an adjustable positioning pin mounted on the top of said frame carried by said plate and adapted to be lowered into engagement with a hole in a last half, said lower pin also adapted to project into the hole from the opposite side of said last half, thereby permitting pivotal movement of the last half in order to permit interior enlargement of the mortise by a routing tool, said work holder so mounted that it may be moved axially toward and transversely of said tool and a routing tool, and means to support the under portion of the last half adjacent the routing tool, said support having a broad bearing surface, means to adjust the position of said frame on said plate, and means to adjust said bearing member on said plate.
6. In a routing machine, a transversely movable supporting plate, means for moving said plate, a frame thereon, said frame being adjustable fore and aft of said plate, a work positioning pin on the bottom of the frame, a second pin over said first pin, a screw journaled in the top portion of the frame, said second pin being carried on said screw, and means for actuating said screw, thereby forming a work-holding pair of pins, and a second similar upper and lower positioning pin with a similar actuating screw forming a second work-holding pair of pins spaced from but adjacent to the first pair of pins.
7. In a routing machine, a transversely movable supporting plate, means for moving said plate, a frame thereon, said frame being adjustable fore and aft of said plate, a work positioning pin on the bottom of the frame, a second pin over said first pin, a screw journaled in the top portion of the frame, said second pin being carried on said screw, and means for actuating said screw, thereby forming a work-holding pair of pins, and a second similar upper and lower positioning pin with a similar actuating screw forming a second work-holding pair of pins spaced from but adjacent to the first pair of pins, and bearing supports having broad bearings for the undersides of the last halves adjacent a routing tool.
8. In a routing machine, a transversely movable supporting plate, means for moving said plate, a work frame thereon, said frame being adjustable fore and aft of said plate, a positioning pin on the bottom of the frame, a second pin over said first pin, a screw journaled in the top portion of the frame, said second pin being carried on said screw, and means for actuating said screw, thereby forming a work-holding pair of pins, and a second similar upper and lower positioning pin with a similar actuating screw forming a second work-holding pair of pins spaced from but adjacent to the first pair of pins.
9. In a routing machine, a transversely movable supporting plate, means for moving said plate, a frame thereon, said frame being adjustable fore and aft of said plate, a work positioning pin on the bottom of the frame, a second pin over said first pin, a screw journaled in the top portion of the frame, said second pin being carried on said screw, means for actuating said screw, thereby forming a work-holding pair of pins, a second similar upper and lower positioning pin with a similar actuating screw forming a second work-holding pair of pins spaced from but adjacent to the first pair of pins, bearing supports having broad bearings for the undersides of the last halves adjacent a routing tool, means for adjusting said frame fore and aft the said plate, and means for adjusting said bearing supports vertically and laterally, and means for adjusting said plate bodily to and from said routing tool.
10. In a routing machine, a transversely movable supporting plate, means for moving said plate, a frame thereon, said frame being adjustable fore and aft of said plate, a work positioning pin on the bottom of the frame, a second pin over said first pin, a screw journaled in the top portion of the frame, said second pin being carried on said screw, means for actuating said screw, thereby forming a work-holding pair of pins, a second similar upper and lower positioning pin with a similar actuating screw forming a second work-holding pair of pins spaced from but adjacent to the first pair of pins, bearing supports having broad bearings for the undersides of the last halves adjacent a routing tool, means for adjusting said frame fore and aft the said plate, and means for adjusting said bearing supports vertically and laterally, said plate being moved laterally by a lever linked to said plate, said lever being pivoted on the main portion of the machine with its handle adjacent the operator.
11. In a routing machine, a transversely movable supporting plate, a base therefor, a rectangular frame mounted thereon, said frame having a base member and a cap member, spaced work-positioning pins mounted on said base member of said frame forwardly of the main portion of said frame, a pair of screws having pins on the lower ends thereof, said screws being journaled in said cap member of said frame, handles for actuating said screws, plate supporting members on said transversely movable supporting plate, plates, consisting of screws with broad heads, carried adjacent on said plate sup-

porting members adjacent said lower pins, parts as anchoring pins, and whereby grooves said heads being adjacent said lower pins may be formed in said last halves by said between said pins and a routing tool, and a routing tool, ¹⁰ routing tool, whereby last parts may be po- In testimony whereof, I affix my signa- sitioned by said pins and be movable rela- ture.

⁵ relative to said routing tool, said pins being in- serted in transverse apertures of said last

GEORGE CLAUSING.
